DIFFERENTIAL HYDRAULIC RAM FOR CRUSHING MILLS

Application filed October 16, 1928. Serial No. 312,867.

My present invention relates to an improvement in crushing mills, and has for its objects the provision of means whereby misalignment, accidental breakage of the crushing rolls or roll trunnions, gearing and appurtenant parts, and so called mill chokes are obviated, and to hold the rolls in their desired position.

In the present instance, the crusher shown 10 is of the type used in sugar mills. In this class of machine in crushing the sugar cane, the cane is thoroughly desiccated or shredded before passing through the rolls. During the pressing operation, the desiccated cane 15 mass or bagasse is fed to and through the rolls somewhat irregularly. That is to say, the mass of bagasse varies in thickness at times, is uneven in spots and therefore is constantly changing the pressure and pressure points between the rolls from end to end.

Even pressure, at present much to be desired, cannot be accomplished due to the unevenness of the presented bagasse. At times 25 the mass is abruptly thick and as it passes through the rolls, causes terrific stresses between the rolls and, in some cases, the material cannot pass through the rolls and therefore chokes the rolls. The pressure exerted by the rolls upon the treated material, as is well known, is controlled by hydraulic means. Hydraulic rams, operating upon opposite ends of the trunnions of the top crusher rolls of such machines are known in the 30 prior art.

The crusher rolls, usually three in number, are all driven by intermeshed gears, one upon each roll. The latter in turn may be driven by a common, pinion driver operated from 40 any suitable power source.

In general practice the roll gears are mounted upon one side of the rolls only and it is to this particular type of machine that my invention is directed.

Accordingly, one of the principal objects of 45 the present invention is to provide means in a crushing mill so arranged that sudden, irregular thicknesses of bagasse may be presented to the mill rolls without causing misalignment of trunnions, bearings and gears

resulting because of suddenly increasing pressure reactions between the rolls, whereby breakage of the driving parts, gears, rolls or trunnions is effectively prevented.

Another object is to provide hydraulic ram 55 means on a sugar cane crushing mill to increase the reaction to the rod pressures, especially of those parts which are used to resist the pressure exerted on the bearings of the crushing rolls, such hydraulic ram means 60 being so arranged and constructed on the gear shaft of one of the crushing rolls, that the hydraulic pressure exerted on the gear side of said shaft is greater than the pressure 65 on the opposite end, thereby constantly maintaining the rolls in their desired, alined position.

Other objects of the invention are to improve generally the simplicity and efficiency 70 of such devices and to provide a crushing mill of this kind which is economical, durable and reliable in operation, and economical to manufacture.

Many of the features of the invention may 75 be used without employing all of them, as some of those which are not essential may be omitted without departing from the spirit of the invention, though such omission may be a greater or lesser extent affect the quality of the product; and for the purpose of describing the invention, there is illustrated in the accompanying drawings one form of apparatus, in which drawings.

Fig. 1 is a partially sectioned side view of 80 a characteristic sugar mill construction, and

Fig. 2 is a sectional view taken on the line 2—2, Fig. 1, looking in the direction of the arrows.

Since the present invention relates only to 85 the control of pressures between the rolls and coacting moving parts, the characteristic crusher illustrated will only be described in such detail as will be sufficient to enable a full disclosure of my invention and its application thereto.

Referring to the accompanying drawings 90 in which like characters of reference indicate the same parts in the different views, the frame or casing of the mill is suitably constructed and in the particular crusher illus- 95 100

trated such frame comprises a base 1 on which rests a supporting member 2 having horizontal surfaces at the top.

These surfaces are spaced from each other 5 at their inner ends, leaving a vertical passage between them, with which passage connect vertical perforations located in the base 1.

Against the supporting member 2 are 10 clamped as by means of bolts 3 and nuts 4, side plates 5 which serve to hold in position the guide 6 for a centrally located movable bearing 7 above said member. Passages 8 are left at the sides of the central portion 6' of 15 the guide 6, the outside width of said central portion being greater than the distance between the lower portions of the perforations located in the frame below the horizontal surfaces mentioned above. A cap 9 is 20 fitted on the upper end of the guide 6 and this guide is firmly connected with the remainder of the machine by king bolts, the upper portions of which are screw-threaded at 10 to receive nuts 11 and lock screws 12. These bolts 25 have also vertical portions 10' which extend through the cap 9 and along the outside of the central guide portion 6', being in engagement therewith. The bolts have downwardly converging portions 10² which extend to the 30 openings left in the base 1 and in the supporting member 2. The lower portions 10³ of the bolts are again vertical and parallel and they are held or secured by means of fastening keys 13 which are passed through the enlarged lower ends of the bolts and engage a suitable bearing plate 14 located in contact with base 1.

The manner of gearing the rolls together forms no part of my present invention and 40 may be the usual one, as follows: The left side of Fig. 1 shows the roll bearings broken away to disclose the upper or floating roll 22 and its integral shaft 22', mounted in the movable or floating bearing 7, the shaft being keyed to a driving gear 25 which in turn meshes with the driving gears 26 of the two 45 lower rolls 27. These latter rolls are constructed similar to the upper roll 22. While the upper roll is movably mounted for vertical motion in its bearings 7, the lower rolls 27 are mounted for free rotation, but are otherwise immovable in their bearings 7'.

As is usual in this type of mill, the two lower rolls 27 are rigidly mounted and, in 50 operation, react against the single upper, floating roll 22. When material passes through the rolls the upper roll lifts slightly but is held to desired, juice-extracting pressure by the hydraulic rams 29, 30 and 31.

It will be noted that the hydraulically- 60 pressed upper roll 22 has one ram 29 on the right hand side of the shaft 22 which is without a gear, and two rams 30, 31 on the left hand or gear side of the shaft thereof, upon 65 which latter side is mounted the gear 25.

Thus, the gear side of the roller 22 has two pressure rams on it and only one on the non-gear side. This arrangement is for the purpose of overcoming a mechanical fault inherent in present day construction. 70

The crusher rolls are mounted as previously herein described. When only one set of rams 29, are utilized on both sides of roller 22, a sudden passage of an abrupt, heavy mass of bagasse between the rolls causes the rolls 75 to move apart, thus pushing upper roll 22 away from lower rolls 27. This action throws the gears 25 and 26 apart, and tends to upset the meshing of the gear teeth of the associate gears. The above results in a cam-like action 80 of the disturbed gears which are then rotating under a heavy load, out of the pitch contact circle, the gears tending to cam themselves upwardly on the gear side only, thus throwing roll 22 out of axis, i. e. at an angle. 85

This action, naturally, throws the upper roll 22 at an angle to its alined operative axis, and strains and injures the bearings, resulting in defective or broken gear teeth or a 90 broken roll shaft, or both, and a serious mis-alinement of the roll with its coordinate parts, such as scraper plates and the like.

This tendency of the gear side to climb up out of operative axis, I have been able to overcome by the arrangement disclosed in Fig. 1, 95 whereby, providing a double ram on the gear side of the mill double, or practically double pressure is applied to the gear side of the upper roll thereby overcoming the reaction tendency of the gears to climb or ride out of 100 mesh.

Since in rams of this nature a single hydraulic pressure creating means, not shown, creates pressure in an accumulator 33, Fig. 1, and the hydraulic pressure therefrom is delivered through piping 34 and 15 to the rams in the caps 9, as shown, it will be seen that I readily and conveniently provide a protection and a remedy for a very common cause of break down in mills, which break downs 110 are expensive, due to stoppage of the mill for repair or replacement when the busy season is on.

Actual practice has proven the worth of this arrangement of hydraulic rams on the upper roll, economy of operation having been effected. The rolls, when arranged as outlined above, adjust themselves quickly to any change of feed in bagasse, the pressure on the shaft of the upper roll and its relative alinement to the cooperating roll remaining constant, thus reducing the crystallization of the metal which takes place with variable pressures. 115

Some of the advantages of the foregoing 120 described inventions are an improvement in sucrose extraction, by reason of keeping the floating roll level, frictions are reduced, improvement in lubrication is accomplished, prevention of unequal wear of bearings and 130

gears, quick automatic adjustment of the floating roll to unequal loads, prevention of crystallization of the metal parts which occurs when abrupt pressure changes take place, 5 and reduction of power required to operate the mill.

The foregoing detailed description has been given for clearness of understanding only. Hence no unnecessary limitations 10 should be understood. The appended claim should be construed as broadly as permissible in view of the prior art, it further being understood that the above invention may be applied to crushers other than that shown 15 above.

What I claim is:

In a sugar cane crushing mill, a frame, a pair of lower rolls mounted therein for free rotation but being fixedly retained relative to 20 the frame, a third floating roller adjacent the lower rolls and being mounted for rotation, all of said rolls being geared at only one end, a hydraulic ram disposed adjacent the third roll on the ungeared end thereof, a double 25 ram, developing substantially double the pressure of said first ram, disposed adjacent the third roll on the geared end thereof to overcome the reaction tendency of the gears to ride out of mesh during sudden passage of 30 a heavy mass of cane between the third and lower rolls, all of said rams being connected to a common pressure line.

Signed at New York in the county of New York and State of New York this 15th day of 35 October, A. D. 1928.

H. J. B. SCHARNBERG.
